CLAIM

The ornamental design for a hydrofoil fuselage as shown and described.

DESCRIPTION

FIG. 1 is a front view of a hydrofoil fuselage showing my new, original, and ornamental design;

FIG. 2 is a rear view of the hydrofoil fuselage of FIG. 1;
FIG. 3 is a left side view of the hydrofoil fuselage of FIG. 1;

FIG. 4 is a right side view of the hydrofoil fuselage of FIG. 1;

FIG. 5 is a top view of the hydrofoil fuselage of FIG. 1;
FIG. 6 is a bottom view of the hydrofoil fuselage of FIG. 1;
FIG. 7 is a front, top, left side perspective view of the hydrofoil fuselage of FIG. 1;

FIG. 8 is a front, top, right side perspective view of the hydrofoil fuselage of FIG. 1;

FIG. 9 is a front, bottom, left side perspective view of the hydrofoil fuselage of FIG. 1; and,

FIG. 10 is a front, bottom, right side perspective view of the hydrofoil fuselage of FIG. 1.

The dashed lines illustrate portions of the hydrofoil fuselage which form no part of the claimed design.

1 Claim, 10 Drawing Sheets
